UNITED STATES PATENT OFFICE.

MAURICE J. SCHLESS, OF NEW YORK, N. Y.

JEWELRY-SETTING.

1,319,251.

Specification of Letters Patent.

Patented Oct. 21, 1919.

Application filed June 27, 1919. Serial No. 307,120.

To all whom it may concern:

Be it known that I, MAURICE J. SCHLESS, a citizen of the United States of America, residing at New York city, New York, have 5 invented certain new and useful Improvements in Jewelry-Settings, of which the following is a specification.

My invention relates to an improved jewelry setting or mounting, and is more 10 especially designed as a setting for diamonds.

It is generally recognized that the manner in which a precious stone, particularly a diamond, is set may very greatly affect its 15 brilliancy. A superior stone if poorly or disadvantageously set will lose a large part of its natural luster, while an inferior stone may be so skilfully set as to have its natural luster materially enhanced. With this condition in mind the principal object of my 20 invention is to provide a setting of such character that the natural brilliancy or luster of a stone set therein will be retained to the fullest extent, and the setting will 25 complement the stone in such a manner that the two will virtually form an entity, the setting contributing to and enhancing the luster of the stone.

Another object of the invention is to so 30 construct the setting that the placing of the stone therein will require but a limited amount of skill on the part of the stone-setter, whereby the character of the work done by highly skilled workmen, and by 35 those less proficient, will be substantially the same.

A further object of the invention is to 40 provide a setting by means of which the appearance of a relatively inferior stone will be improved to such an extent as to make it difficult for anyone but an expert to distinguish the same from a stone of superior quality.

Stated in general terms, the invention consists 45 in a setting having a faceted portion which is designed to complement and practically merge with the faceted upper portion of a precious stone, so that the stone and that portion of the setting will appear as one.

50 The invention is illustratively exemplified in the accompanying drawing, in which—

Figure 1 is a plan view of my improved setting showing a diamond in position therein; Fig. 2 is a side elevational view with 55 a part of the setting or mounting broken away to better illustrate the manner of retaining the stone in position; Fig. 3 is a

horizontal sectional view in the line 3—3 of Fig. 2; Fig. 4 is a plan view of a blank for a modified form of the lower part of the setting; Fig. 5 is a side elevational view showing the blank of Fig. 4 formed up to receive the upper part of the setting; Figs. 6, 7 and 8 are views of further modified forms for the lower part of the setting. 65

In all embodiments of the invention I prefer that the form of the upper part of the setting which adjoins the upper portion of the stone shall be the same, while if desired the lower part of the setting may be varied in 70 different forms of the invention.

Referring in detail to the drawing, and particularly to Figs. 1 to 3, the upper portion of the diamond is denoted 10, the girdle 11, and the base 12. As is usual, the upper 75 portion and base are faceted in order that the stone may reflect light and thus have that luster which is one of the distinguishing characteristics of a diamond.

The setting for the stone comprises a 80 crown portion 13 and a base portion denoted generally as 14, which portions may or may not be integral, as desired. The crown portion 13 is faceted like the diamond itself, and consists of a substantially frusto-conical 85 plate having at what would be its apex an opening for the reception of the stone. In order that the stone may be firmly seated the wall of the opening in the crown portion 13 is provided with an annular groove 13^a 90 wherein the girdle 11 of the stone is received. The construction somewhat resembles the bezel of a watch case for retaining the glass in position. The crown portion 13 may be of metal capable of taking a high 95 polish, and I have found that platinum and white gold are well adapted for the purpose.

The base portion 14 of the setting comprises a hub or connecting center 15 having radiating arms 16 which have their outer 100 ends connected to or formed integral with the lower edge of the crown portion 13. The arms 16 constitute a desirable form of construction for the lower part of the setting inasmuch as the spaces therebetween permit 105 light to strike and be reflected from the lower part of the stone, and also because access may be had through these spaces to the inside of the setting for cleaning purposes.

In Fig. 4 I have shown a blank from 110 which a modified form of the lower part of the setting may be formed up. In this figure 15^a is the hub or connecting center from

- which the substantially triangular segments 16^a radiate, each segment having the opening X therein. When the blank is formed up, it has the appearance indicated in Fig. 5, 5 the lateral edges of the segments 16 being closely juxtaposed, and the entire structure being substantially an inverted cone, much like the lower portion of the setting shown in Figs. 1 to 3.
- 10 The blank of Fig. 6 is punched or died out of a metal sheet, to provide the center portion 15^b and the radiating segments 16^b which, unlike the segments 16^a of Fig. 4, are all connected together and have their 15 outer edges 16^x pointed or star shaped. The segments are shaped somewhat like a frame having the depressed body portion a and the relatively raised edge or rim b. Each segment also has the central opening Y.
- 20 The structure of Fig. 7 resembles that of Fig. 6 the difference being essentially that the upper edge 16^y is plane and not serrated as is the case with a lower setting portion made from the blank of Fig. 6.
- 25 In Fig. 8 there is disclosed a setting portion 16^c which is faceted and provided with openings Z. The upper edge of the setting portion is castellated, that is it is formed with spaced projections 16^z.
- 30 It will be understood that the lower setting portion may be made of any suitable material, such as glass or metal, the latter being preferred.

Copies of this patent may be obtained for five cents each, by addressing the "Commissioner of Patents,
Washington, D. C."

The complete setting, with the stone held therein, may be mounted in a ring, brooch, 35 bracelet, or any other desired object, in a manner well known in the jeweler's art.

What I claim is:—

1. A jewelry setting having a faceted crown portion provided with an opening for 40 the reception of a stone.

2. A jewelry setting having a substantially conical faceted crown portion provided with an opening for the reception of a stone. 45

3. A jewelry setting having a faceted crown portion provided with a substantially central opening, the wall of said opening being grooved to receive the girdle of a stone. 50

4. A jewelry setting, comprising a faceted crown portion provided with an opening for the reception of a stone, and a base portion having spaced light admitting openings therein. 55

5. The combination with a faceted precious stone, of a setting therefor including a faceted metal crown portion complementary to the faceted portion of the stone.

In testimony whereof I have affixed my 60 signature in presence of two witnesses.

MAURICE J. SCHLESS.
